United States Patent Office

Des. 184,691
Patented Mar. 24, 1959

184,691

TENT

Jerry Siegel and Joanne Siegel, Seaford, N.Y., assignors to Fulton Bay & Cotton Mills, Atlanta, Ga., a corporation of Georgia

Application March 3, 1958, Serial No. 49,861

Term of patent 3½ years

(Cl. D88—3)

We claim:

The ornamental design for a tent, as shown.
